UNITED STATES PATENT OFFICE.

ALFRED MAURICE MAZER, OF JEANNETTE, PENNSYLVANIA.

PROJECTILE.

No. 855,466.

Specification of Letters Patent.

Patented June 4, 1907.

Application filed May 29, 1906. Serial No. 319,273.

To all whom it may concern:

Be it known that I, ALFRED MAURICE MAZER, a citizen of the French Republic, residing at Jeannette, in the county of Westmoreland and State of Pennsylvania, have invented certain new and useful Improvements in Projectiles, of which the following is a specification, reference being had therein to the accompanying drawing.

This invention relates to projectiles, and its primary object is to increase the trajectory of a projectile, and to thus increase the range of a gun.

Other objects of the invention will be disclosed hereinafter as the description proceeds.

The present invention is based upon the theory that it is possible to increase the trajectory of a projectile by so weighting the projectile as to direct its point or nose so that it will follow a horizontal path for the maximum length of time, the weight being movable within the projectile, and provided with mechanism for sliding it at first slowly and then with accelerated speed according to the curve of the trajectory.

If a gun on a high elevation is placed with the axial center of its bore on a horizontal plane, a projectile fired therefrom, will under the force of the charge, follow a horizontal path for a little time, and then begin to pass below the horizontal, that tendency increasing more and more as the projectile travels, the point or nose being the lowest point in the arch described by the travel of the projectile, and if no obstacle is encountered, the projectile will descend in space point downward as long as its rotary motion continues. To overcome this tendency of the projectile to pass from the horizontal path to one approaching the vertical is the design of my invention; and by so doing, I increase the range and danger zone of the gun, and facilitate range finding.

With these ends in view the invention consists of a projectile of the novel construction hereinafter described and illustrated in the accompanying drawings, which form part of this specification, and in which,

Figure 1 is a central vertical section of a projectile embodying the invention, Fig. 2 is a similar view of the central portion of the projectile on a larger scale, and of slightly modified construction, Fig. 3 is a transverse

section on the line $x-x$ of Fig. 2, Fig. 4 is a central vertical section on an enlarged scale of one of the impact fuses supported within the projectile, Fig. 5 is a central vertical section of a portion of a modified form of projectile, and Fig. 6 is a transverse section on the line $y-y$ of Fig. 5.

The shell of the projectile comprises three detachable hollow casings designated respectively by the reference numerals 1, 2 and 3; the casing 1 providing a powder chamber 4, and the point or nose 5. The central casing 2 is adapted to contain the mechanism employed, and the rear casing 3 affords a rear powder chamber 6.

The rear end of the casing 1, and the front end of the casing 3 are internally recessed and screw-threaded to receive externally threaded flanges 7 projecting from the ends of the central casing 2. Peripherally threaded disks 8 and 9 engaging inwardly extending threaded flanges 10 of the casing 2 provide partitions dividing the mechanism chamber from the two powder chambers 4 and 6.

The rear wall 11 of the chamber 6 and the disk 8 serving as the rear wall of the chamber 4 are each formed with a central forwardly projecting threaded socket 12 to receive an impact fuse 13. The construction of these fuses is shown in Fig. 4 and will now be described. The cylindrical barrel 14 of the fuse is formed at its rear end with a threaded collar 15 fitting the socket 12. The front end of the barrel is closed by a diaphragm 16 having perforations 17 formed therein and carrying on its rear face a fulminate 18. Upon the forward end of the barrel 14 is fitted a powder chamber 19 adapted to contain slow-burning powder 20.

In front of the chamber 19 is a chamber 21 to contain rapid-combustion powder 22, and closed at its outer end by a perforated cap 23. The two chambers 19 and 21 communicate by means of registering openings 24, and the powder in the chambers 4 and 6 is thus exploded, the openings 24 in the cap 23 allowing the flame to reach said chambers. Within the barrel 14 is supported a hammer 25, having a stem 26 carrying a head 27 at its rear end. The hammer is supported longitudinally within the barrel by means of spring clips 28 preferably held in place by a screw plug 29 fitting within the rear end of the barrel, and grasping the stem

26 in front of the head 27, the latter serving as a stop to prevent forward movement of the hammer until the projectile strikes an obstruction, when its momentum will release 5 the hammer to explode the fulminate 18.

Referring now to Figs. 1 and 2, I will describe the mechanism arranged within the central chamber 2. The numeral 30 designates a trunnion screwed into a central 10 threaded opening formed in the partition 8, to revolve with the latter. The rear end of the trunnion 30 is formed with a bearing 31 which will be referred to hereinafter and in front of said bearing a gear pinion 32 is fixed 15 upon the trunnion. Loosely mounted upon the trunnion between the pinion 32 and the partition 8 is a hanger 33 provided at its lower end with a bearing for the forward end of a shaft 34 upon which is fixed a gear wheel 20 35 meshing with the pinion 32. The rear surface of the partition 8 is formed with an annular rib 36 surrounding the trunnion to serve as a reduced friction surface for the hanger 33. 37 designates a shaft supported 25 loosely at its front end within the bearing 31 and at its rear end within a bearing 38 formed centrally of the partition 9. I preferably provide ball bearings for this shaft as shown in the drawings. Fixed to the shaft 37 is a 30 gear wheel 39 meshing with a pinion 40 fixed upon the shaft 34. Suspended from the shaft 37 is a pendulum 41 provided at its upper end with a sleeve 42 through which the shaft 37 extends and at the center of its body 35 portion with an opening 43 through which the shaft 34 extends, said opening 43 having a central annular rib 44 to reduce the friction between the shaft and pendulum. The shaft 37 has a spiral groove 45 extending from a 40 point in rear of the gear wheel 39 to the rear end of the shaft. A screw 46 extends through the sleeve 42 and projects into the groove of the shaft so that the revolution of said shaft will move the pendulum rearward as will be 45 further referred to. The pitch of the forward convolution 47 of the groove in the shaft 37 is vertical, for a short distance to allow the projectile to travel for a time in a horizontal plane under the force of the explosion, while the pitch of the remaining convolutions is increased or of graduated inclination to effect a gradually increasing rearward movement of the pendulum. The 50 pendulum is on the center of gravity, when the projectile is fired, and as long as the projectile travels in a horizontal plane under the force of the explosion the center of gravity is maintained by the vertical convolution of the groove in the shaft. To maintain the 55 pendulum in its normal position, a threaded pin 48 extends through an opening in the casting 2 below the pendulum, said pin engaging in a slot 49 formed on the under surface of the pendulum. As the projectile is placed in the 60

gun, this pin 48 is removed to release the 65 pendulum.

The operation of the mechanism constructed and arranged as above described is as follows:—When the projectile leaves the gun and is projected under the force of the 70 charge its rapidly revolving motion is imparted to the trunnion 30, and through the intermediary of the pinion 32 and gear wheel 35, the shaft 34 is revolved, thus revolving the pinion 40, gear wheel 39, and shaft 37. 75 The pitch of the convolution of the groove 45 is calculated with reference to the curve of the trajectory, the first convolution as above stated following a line perpendicular to the shaft to permit the projectile to maintain 80 itself along a horizontal path under the force of the charge. As the projectile proceeds the pendulum will be moved rearwardly by the screw 46 traveling in the groove 45, thus displacing or changing the center of gravity 85 and overcoming the tendency of the point or nose of the projectile to drop below a horizontal plane. As the projectile moves ahead it gradually loses its force and becomes more susceptible to the attraction of gravitation 90 and the resistance of the air, but its tendency to plunge downward will be overcome by the rearward shifting of the weighted pendulum and the consequent shifting of the center of gravity until the screw 46 reaches the rear 95 end of the groove when the projectile will plunge, and curve to the ground. It will be apparent however, that this will not occur until after the projectile has traveled a much greater distance than it could have covered 100 without being equipped with the shifting weighted device. When the point of the projectile contacts with an obstruction its momentum releases the impact fuses as above explained, and the explosion of the 105 fulminate by the hammers 25 first ignites the slow-burning powder in the chamber 19 and subsequently the quick-combustion powder in the chamber 21, and in the chambers 4 and 6.

In Figs. 5 and 6, I have shown a modified construction in which the partition 8^a between the powder chamber 4 and the mechanism chamber is hollowed out as at 50 to conform to the contour of a supplemental 110 weight 51 carried upon the forward end of the shaft 34, the latter being extended to receive said weight. The function of this supplemental weight is to maintain the gear wheel 35, and pinion 40 in proper working 115 position, and said weight is free and balanced on the shaft 34. It may be of any preferred form or contour.

The utility and advantages of my improvement will be readily understood by 120 those skilled in the art to which it pertains, and I would have it understood that the invention is not restricted to the precise con-

struction shown in the drawings, but includes all such modifications and variations in the minor details as may be resorted to without departing from the scope of the claims.

What I claim and desire to secure by Letters Patent, is:—

1. The combination with a projectile, of means carried therein for increasing the horizontal trajectory, said means being operated by the rotary motion of the projectile.

2. A projectile comprising a plurality of independent chambers or compartments, in combination with mechanism supported within one of said compartments for maintaining the projectile in a horizontal position during flight, said mechanism being operated through the rotary motion of the projectile.

3. The combination with a projectile, of mechanism carried therein for maintaining the projectile in a horizontal position during flight, comprising a movable weight or pendulum, and means operated by the rotary motion of the projectile for moving said weight or pendulum rearward.

4. The combination with a projectile, of a revoluble shaft supported within the projectile, and disposed longitudinally thereof, a weight movable upon said shaft, and means driven through the rotary motion of the projectile for moving said weight.

5. The combination with a projectile comprising a plurality of chambers, of mechanism supported within one of said chambers for maintaining the projectile in horizontal position during flight consisting of a revoluble shaft, a weight suspended therefrom, means for revolving said shaft through the rotary motion of the projectile, and means for effecting the rearward movement of the weight upon said shaft.

6. The combination with a projectile, of mechanism arranged therein comprising a longitudinally disposed revoluble shaft formed with a spirally disposed groove, a weight suspended from said shaft, a device connected with said weight and projecting into said groove, and a train of gearing driven by the rotary motion of the projectile for revolving said shaft.

7. The combination with a projectile comprising a plurality of detachable casings, of mechanism supported within one of said casings and comprising a longitudinally disposed spirally grooved shaft, a weight suspended from said shaft, a fixed trunnion adapted to revolve with the projectile, a gear pinion on said trunnion, and a train of gearing driven by said pinion to revolve said shaft.

8. The combination with a projectile, of a longitudinally disposed grooved shaft supported within the projectile, a weight suspended from said shaft, and means driven by the rotary motion of the projectile for moving said weight rearward to tend to elevate the point or nose of the projectile.

9. The combination with a projectile, of a longitudinally disposed grooved shaft supported within the projectile, a weight suspended upon said shaft, means carried by said weight to engage the groove of the shaft, a gear pinion mounted upon a fixed portion of the projectile, a shaft extending through said weight, a gear wheel upon said latter shaft meshing with said pinion, and gearing for revolving said grooved shaft from the shaft which extends through the weight.

10. A projectile having a forward and a rearward powder chamber and a mechanism chamber interposed between said powder chambers, in combination with mechanism operated by the rotary motion of the projectile for maintaining the projectile in horizontal position along its trajectory.

11. The combination with a projectile, of a longitudinally disposed grooved shaft supported therein, means for revolving said shaft from the rotary motion of the projectile, a weight suspended from said shaft and adapted to be moved rearward by the revolution of said shaft, and a supplemental weight supported adjacent to the movable weight.

In testimony whereof I affix my signature in the presence of two witnesses.

ALFRED MAURICE MAZER.
